(73) Assignee: **SRAM Corporation**, Chicago, IL (US)

(57) **CLAIM**

(21) Appl. No.: **29/121,457**

The ornamental design for an integrated rider-controlled support unit for handlebar-steered vehicles, as shown and described.

(22) Filed: **Apr. 6, 2000**

DESCRIPTION

(51) LOC (7) Cl. **12-16**
(52) U.S. Cl. **D12/178**
(58) Field of Search D12/111, 114, D12/178; 74/551.1-551.9

FIG. 1 is a perspective view of an integrated rider-controlled support unit for handlebar-steered vehicles;

FIG. 2 is a front view thereof;

FIG. 3 is a rear view thereof;

FIG. 4 is a top view thereof; and,

FIG. 5 is a bottom view thereof.
